UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

FIREPLACE-STOVE.

SPECIFICATION forming part of Letters Patent No. 508,341, dated November 7, 1893.

Application filed February 28, 1893. Serial No. 464,000. (No model.)

To all whom it may concern:

Be it known that I, THOMAS I. RANKIN, a citizen of the United States, residing in Philadelphia, Pennsylvania, have invented certain 5 Improvements in Fireplace-Stoves, of which the following is a specification.

The object of my invention is to so construct a fire place stove that the dust flue will be within the limit of the stove casing, and the 10 apron around the hearth can be removed so as to clean under the hearth, as fully described hereinafter, reference being had to the accompanying drawings, in which—

Figure 1, is a front view of my improved 15 fire place stove. Fig. 2, is a vertical section. Fig. 3, is a sectional plan view; and Fig. 4, is an enlarged perspective view of a portion of the hearth and apron, showing the apron detached.

20 Stoves of the class shown in the drawings are intended to be inserted into fire place openings, to take the place of the ordinary open grates which are built in the fire place. These stoves are set up and completed before they 25 are inserted into the fire place, and they simply have to be connected with the flue.

It has been the endeavor of manufacturers to economize in space, especially in depth, and yet have sufficient grate surface without projecting the stove into the room, and further 30 these stoves have raised hearths under which dust and dirt will accumulate, and as ordinarily made the aprons of the hearth are either rigidly secured to the hearth, or are set first 35 and the hearth placed upon them, so that it is impossible to clean the space under the hearth without removing the stove.

Referring to the drawings, A is the outer 40 frame of the stove adapted to rest against the jamb of the fire place opening, and is secured to the body portion B in any suitable manner. This body portion is adapted to fit in the fire place opening as shown by dotted lines in Fig. 3, and I so arrange it that the back will rest 45 against the back of the fire place, thus utilizing the full opening for grate surface.

C is the grate which may be of any form desired. I have shown in the drawings a tilting grate.

50 D is the front of the fire box, and the back

of the fire box has a fire brick lining E, and side brick lining E'.

F is the ash-pit formed by depressing a portion of the hearth G, and extends under the grate to the rear of the stove.

As shown in Figs. 2 and 3, I cut a vertical groove in the fire brick E, and secure to the back of the body portion B a flanged plate h forming a dust flue H within the body portion, so that the body portion can rest directly 60 against the back of the fire place and thereby increase the grate surface. This plate h extends up into the flue I above the deflecting brick i, and is provided with a damper J attached to an operating rod j, which when drawn 65 out, turns the damper so as to open the flue, and thus allows the dust from the ashes when the fire is being raked, to pass up the dust flue instead of through the fire and into the room. The flue I communicates with the chimney through the passage i'. The usual blower is used, and the usual ash pit cover is also used, which can be removed bodily from the stove or pivoted in the usual manner.

The hearth G is raised a certain distance 75 above the floor level to give the ash pit sufficient depth, and to allow for the free circulation of air between the stove and the wall of the fire place, and in order to properly finish the hearth an apron or filling plate K extends 80 from the hearth to the floor, and as this apron must have openings for the passage of air, dust and dirt will accumulate under the hearth, and as heretofore made, these aprons are permanently secured to or form part of the hearth, 85 they cannot be removed without drawing the stove out of the fire place.

As shown in Fig. 4, I form a depressed rib or flange g on the edge of the hearth G, and cast on this flange, pins g', at intervals.

On the upper edge of the apron K is an internal flange k having openings k' adapted to the pins, so that when the apron is placed over the flange on the hearth, the pins will pass into the openings and hold the apron in 95 place. The apron may be made in two parts as shown in Fig. 1, and the parts may be secured together by a plate shown by dotted lines in said figure. Thus the apron can be readily removed from the hearth, and the floor 100

under the hearth can be cleaned when the room is cleaned, and replaced without moving the stove.

I claim as my invention—

- 5 1. The combination in a fire place stove, of the body portion, frame and hearth, with a dust flue formed on the inside of the body portion at the back, a metal casing surrounding the body portion, and communicating at its lower end with the ash pit, and at its upper end with the smoke flue, substantially as described.
- 15 2. The combination in a fire place stove, of the body portion, a plate secured to the inside of the body portion and forming a dust flue within the furnace body, the fire brick having a vertical channel at the back for the said flue, the lower portion of the flue communicating with the ash pit and the upper portion with 20 the smoke flue, substantially as described.
- 25 3. The combination in a fire place stove, of the body portion formed of a metal casing adapted to rest against the rear wall of the fire place opening, a frame and hearth secured thereto, a grate dividing the ash pit from the fire box, fire brick at the back and sides of the fire box resting against the metal casing, the rear fire brick being cut away forming a channel, a vertical flange plate secured to the 30 inner side of the metal casing at the back forming a dust flue, the lower portion of said flue communicating with the ash pit, and the

upper portion communicating with the smoke flue, with a damper in the upper portion, a rod for said damper extending through the frame 35 and supported thereby, substantially as described.

4. The combination in a fire place stove, of the elevated hearth, a depressed ash pit formed integrally therein, with an apron mounted on 40 said hearth and depending therefrom, said apron being detachably secured to the hearth, substantially as described.

5. The combination in a fire place stove, of the elevated hearth having a depressed ash 45 pit, a flange on said hearth, with a flanged apron, the flange of the apron resting on the flange of the hearth, projections on one part adapted to fit in holes in the other part, substantially as described.

6. The combination in an open fire place, of the elevated hearth G, having a depressed flange g, pins g' on said flange with an apron K having an internal flange k at its upper edge, with openings k' in said flange into which 55 the pins extend when the apron is mounted upon the hearth, substantially as described.

In testimony whereof I have signed my name to this specification in the presence of two subscribing witnesses.

THOMAS I. RANKIN.
